Des. 182,119
Patented Feb. 18, 1958

182,119

COMBINED KNOB AND ESCUTCHEON

Carl C. Hillgren, Newport Beach, Calif., assignor to Hillgren Manufacturing Company, Huntington Park, Calif., a corporation of California

Application October 8, 1956, Serial No. 43,263

Term of patent 14 years

(Cl. D50—6)

FIG. 1.

FIG. 2.

FIG. 3.

Figure 1 is a front perspective view of a combined knob and escutcheon, showing my new design.

Figure 2 is a front elevational view.

Figure 3 is a side elevational view.

I claim:

The ornamental design for a combined knob and escutcheon, substantially as shown.
